COMBINED CABINET AND TOWEL RACK

Charles H. Greenlee, New York, N. Y.

Application September 21, 1953, Serial No. 26,870

Term of patent 14 years

(Cl. D44—29)

To all whom it may concern:

Be it known that I, Charles H. Greenlee, a citizen of the United States of America, residing at New York, New York, have invented a new, original, and ornamental Design for a Combined Cabinet and Towel Rack, of which the following is a specification, reference being had to the accompanying drawing, forming a part hereof.

Figure 1 is a front elevational view of a combined cabinet and towel rack embodying my new design.

Figure 2 is a side elevational view; and
Figure 3 is a top plan view thereof.

The sides opposite Figures 2 and 3 are substantially like the ones shown and the rear view thereof is plain.

The drawing is shaded to represent ceramic tile panels disposed in the front of the upper portion of the cabinet.

I claim:

The ornamental design for a combined cabinet and towel rack, as shown and described.

CHARLES H. GREENLEE.
